CLARK A. TERRY, OF GLENS FALLS, NEW YORK, ASSIGNOR TO INTERNATIONAL PAPER COMPANY, A CORPORATION OF NEW YORK

HYDRAULIC TURBINE

Application filed June 27, 1925. Serial No. 39,904.

This invention relates to hydraulic turbines and aims to prevent vibration due to the constant making and breaking of the vacuum in the draft tube and tail race, and to increase the efficiency of operation.

5 the efficiency of operation. It is well known to those familiar with the operation of hydraulic turbines, that there is a tendency of the water column to pulsate in the draft tube, which is more or less pronounced according to the varying conditions 10 with respect to the changes in load, the action of the governor, the sudden closing of the turbine gates, and other conditions encountered in the practical operation of the mechanism. The momentum of the water column 15 in the draft tube under the conditions mentioned, causes the column to break, and on the column being arrested by the creation of the vacuum due to the break, the column is thrown upwardly again by the atmospheric pressure, and these actions being rapidly repeated, result in violent pulsations of the water column, with the vacuum constantly making and breaking in the draft tube and 20 tail race, and subjecting the mechanism to violent, injurious and annoying vibrations which greatly interfere with the efficiency of 25 operation.

In accordance with the present invention
30 this objectionable action of the turbine is pre-
vented by the provision of means of improved
form and construction which, on the tendency
of the creation of a vacuum in the draft tube
by the break of the water column, will act
35 automatically to admit air to the water col-
umn and thus check the creation of a vacuum
such as would bring about the objectionable
actions above described.

40 In its more detailed form the invention
45 consists of a suction relief instrumentality
in the form of a valve applied in a passage
leading from the outside atmosphere to the
interior of the draft tube, which valve is
spring pressed on its seat so as to prevent the
45 escape of water outwardly from the draft
tube under normal conditions of operation,
but is capable when the force of the spring
is overcome, to yield and open inwardly and
thereby admit air to the draft tube, such
50 opening movement of the valve being effect-

ed automatically when the suction of the water in the draft tube reaches a predetermined point.

The invention consists also in the provision of means for muffling the action of the valve in its opening and closing movements, so as to silence its operation to a minimum. 55

In the accompanying drawings:

Fig. 1 is a sectional elevation of a hydraulic turbine having my invention applied thereto. 60

Fig. 2 is an elevation partly in section on an enlarged scale of the air admission valve mechanism.

Fig. 3 is a cross section through the same on the line 3-3 of Fig. 2.

Referring to the drawings:

1 designates a hydraulic turbine provided as usual with the rotor 2 carried by a rotor shaft 3, to which rotor water is admitted through the intake chamber 4 surrounding the rotor, and from which the water flows downwardly through a draft tube 5 and finds its escape through a tail race 6.

7 designates a valve mechanism, which in accordance with my invention, is applied to the outer end of a passage or pipe 8 leading from the outside atmosphere and communicating with the interior of the draft tube. 75

extending with the interior of the draft tube. The pipe 8 has its inner end exposed within the draft tube and extends through the wall 80 thereof and has its outer end disposed in a lateral passage at the lower end of the inspection pit 9 leading upwardly to the outside air through the masonry surrounding the turbine. The valve mechanism 7 comprises a valve casing 10 connected at its inner end to the outer end of the pipe 8 and connected at its outer end to the inner end of a cylindrical perforated shell 12. The valve casing is provided with a valve seat 13, 90 against which seats an inwardly opening valve 14 carried by a valve stem 15 which is guided at its inner end in a spider 16 fixed in the valve casing. The valve stem extends outwardly within the cylindrical shell 12 and through the outer end of the same and is acted on by a spring 17 surrounding the outer exposed end of the stem and bearing against the end of the cylindrical shell and against an adjustable head 18 on the end of the stem, 95 10

the tendency of the spring being to hold the valve yieldingly on its seat, and thereby close the communication of the pipe 8 with the outside atmosphere.

5 The valve thus applied and held yieldingly to its seat by the spring, will prevent the escape of water from the draft tube and is capable of opening inwardly when the suction of the water within the draft tube reaches a predetermined degree and the force of the spring is overcome, such inward opening of the valve permitting air to flow inwardly through the perforated shell and pipe 8 and into the draft tube and thus acting to relieve 10 said abnormal suction. Under the normal operation of the turbine, with the water flowing downwardly through the draft tube, the valve will be held closed by its spring, thereby maintaining that degree of suction of the water in the draft tube which is characteristic 15 of the normal action of the downwardly flowing water. When however the conditions are such that the suction of the water increases to an abnormal degree with a tendency 20 of the water column to break and the creation of a vacuum, the valve will be opened automatically against the force of the spring by the atmospheric pressure, and air will be admitted to the draft tube and the tendency 25 of the column to break will be checked. In this manner the valve will act to automatically prevent pulsations and vibrations of the water column, and while opening automatically to admit air according to the degree of 30 suction obtaining within the draft tube, it will under normal conditions of operation prevent the escape of the water from the draft tube and will maintain that degree of suction in the tube which is characteristic of the normal operation of the turbine.

40 In order to reduce the sound of the inrushing air on the opening of the valve and relieve the same of undue noise, means are provided to muffle the mechanism, which means in the present case is in the form of a mass 19 of curled hair or like material which is packed in the perforated shell in the annular space between the same and an internal perforated tube 20 sustained centrally within the shell 45 and surrounding the valve stem. The mass of material thus applied while permitting the passage of the air through the perforated shell and perforated tube and its entrance into the draft tube on the opening of the valve, will effectually silence the action of the rapidly flowing stream of air and will at the same time act to filter the air.

50 The improved mechanism constructed and applied as above described is positive and reliable in action, is adapted for application to any form of draft tube, and is readily adjustable so as to operate under varying degrees of suction within the tube according to the varying conditions encountered in practice. By preventing the pulsations and

vibrations of the water column, which are not only annoying and disturbing in the plant but frequently of an injurious and destructive character, the efficiency of the turbine is greatly increased and safety in operation assured.

55 It may be desirable to apply to the pipe 8, a vacuum gage 21, and to apply a gate valve 22 to the pipe between the gage and valve mechanism 7, as shown in Fig. 2.

60 In the foregoing description and accompanying drawings I have set forth one form of embodiment of the invention by way of example, but it will be manifest to the skilled mechanic that the details of the mechanism and its mode of application may be variously changed without departing from the spirit of the invention; and it will be understood that the invention is not limited to any particular form or construction of the parts except in so far as such limitations are specified in the claims.

65 Having thus described my invention, what I claim is:

1. In combination with a hydraulic turbine of the suction type having a draft tube in which the water column submerges the turbine rotor, an air inlet mechanism associated with the draft tube and comprising an inwardly opening valve and adjustable means to control the opening of said valve, and responsive automatically directly to a predetermined degree of suction of the water therein to admit air automatically to the water column when said degree of suction is reached; whereby vibration of the water column will be prevented.

70 2. In combination with a hydraulic turbine of the suction type having a draft tube in which the water column submerges the turbine rotor, an air inlet mechanism associated with the draft tube and comprising an inwardly opening valve and adjustable means to control the opening of said valve, and responsive automatically directly to a predetermined degree of suction of the water therein to admit air automatically to the water column when said degree of suction is reached, said valve when closed acting to prevent the escape of water through it.

75 3. In combination with a hydraulic turbine of the reaction type having a draft tube in which the water column submerges the turbine rotor, an air inlet valve applied to said draft tube and an adjustable spring acting on said valve to hold it yieldingly closed, said valve being constructed to be opened automatically by the suction of the water in said tube when said suction reaches a predetermined degree; whereby air will be admitted automatically to the water column and vibration of the same will be prevented.

80 4. In combination with a hydraulic turbine of the reaction type having a draft tube in which the water column submerges the

turbine rotor, a normally closed inwardly opening air inlet valve applied to said draft tube, said valve being constructed to be automatically opened and admit air to the draft tube when the suction of the water in said tube reaches a predetermined degree, and adjustable means to control the opening of said valve whereby the vibration of the water column, and the escape of the water through the valve, will be prevented.

In testimony whereof, I have affixed my signature hereto.

CLARK A. TERRY.
